UNITED STATES PATENT OFFICE.

HENRY AMACHER, OF CULLOM, ILLINOIS.

CLOTHES-LINE.

1,148,818.

Specification of Letters Patent.

Patented Aug. 3, 1915.

Application filed October 1, 1914. Serial No. 864,499.

To all whom it may concern:

Be it known that I, HENRY AMACHER, a citizen of the United States, residing at Cullom, in the county of Livingston and 5 State of Illinois, have invented certain new and useful Improvements in Clothes-Lines, of which the following is a specification.

This invention relates to spring grips, and more particularly relates to a novel adaptation 10 of the latter in forming a clothes line.

As a particular object, this invention contemplates the provision of a clothes line formed of a series of spring grips such that it may be operated by a person remaining 15 standing at one point and such that the clothes will be resiliently retained upon the line for any desired length of time.

An object of equal importance is to provide a protector for said grips to guard 20 against the action thereon of the elements and to also construct a clothes line of the foregoing type with such regard to proportion, number and arrangement of parts as to render it capable of being cheaply 25 manufactured as well as durable and efficient in operation.

The above and additional objects which will become apparent as this explanatory 30 description proceeds, are accomplished by such means as are illustrated in the accompanying drawings, described in the following specification, and then more particularly pointed out in the claims which are appended hereto and form a part of this 35 application.

With reference to the drawings, wherein there is illustrated the preferred embodiment of this invention as it is reduced to practice, and throughout the several views, 40 of which like characters of reference designate similar parts:—Figure 1 is a side elevation of one of the clothes lines comprehended by this invention as set up and ready for use, the supports therefor being 45 only fragmentarily shown, Fig. 2 is a perspective view of one of the spring grips shown in the closed position, Fig. 3 is a similar view of a grip as it appears when open, and Fig. 4 is also a perspective view 50 showing a grip inverted and provided with one of the protectors, the latter being also illustrated in dotted lines in Figs. 2 and 3.

There is illustrated a rotatable clothes line mounted for endless movement upon a 55 pair of pulleys 5 which are in turn rotatably supported by bracket arms 6 of any desir-

able construction although formed with an arcuate intermediate portion 7 for the obvious purpose of permitting movement thereby of the grips of this invention as will appear. These brackets are removably received as indicated at 8 in suitable posts or standards of any customary variety.

The clothes line consists of a series of 60 spring grips linked in alinement and of sufficient number to extend between the pulleys 5 to form the upper portion of the clothes line circuit, the lower portion of which is formed by the continuous wire 10. Each of the spring grips which are illustrated 65 to advantage in Figs. 2, 3 and 4 consists of the base or main spring 11 and a pair of jaws 12 loosely connected thereto.

The spring 11 is formed at one end with an eye 13 at right angles to which is the continuation 14 integrally formed at its other end with the loop 15 parallel to the eye 13 and equally spaced therewith from the linear portion 14. A continuation 16 is aligned with the portion 14 of this spring and 70 formed upon the other end of the loop 15, itself terminating in the arcuate V-shaped resilient arm 17, the end of which is formed with a large eye 18 loosely slidable upon the similar extensions 19 of the jaws 12. These 75 jaws are substantially U-shaped and have eyes 20 formed upon each of the extensions 19, one pair of similar eyes being received in the spring eye 13 and the other pair in the loop 15 as is clearly illustrated. Links 80 21 serve to connect successive spring grips of the described construction while the wire 10 is similarly formed with loops 22 for connecting the terminal grips with each other about the pulleys 5.

It will be understood of course that the 85 resilient arm 17 normally tends to maintain the jaws 12 in the closed or gripping position illustrated in Fig. 2 such position being automatically assumed by the grip, after 90 the operator's grip is released whereby the spring arm 17 is depressed to enable the jaws 12 to pivotally open in their respective loops for the reception of clothes therein.

The grips when not in use are permitted 95 to occupy the position shown in dotted lines in Fig. 1, but when it is desired to put the clothes line in service the operator can take his position at any point and by intermittently pulling upon the wire 10 in a constant direction will successively position adjacent to himself the several spring grips.

each in turn, which may then be given the clothes they are expected to support in the obvious manner. Similarly, when the clothes have been dried it is possible for 5 the operator to take his station at any one point and successively relieve each grip of the clothes carried thereby, so that when the last grip has been reached the whole number will form the under portion of the 10 clothes line circuit in which position they are to be left until again utilized as clothes carriers. In this position, as just previously set forth, it will be seen that the protector plate 23 which, it may be noted, is preferably formed from some non-rusting material, is provided with apertures 24 to enable the plate to loosely slide upon the extensions 19 of the jaws 12. When the grips are in their inverted position as shown in 15 Fig. 4, it will readily be appreciated that these protectors prevent inclemencies of weather from rusting or otherwise injuring the grips so that they might be injurious in turn to clothes they support.

20 25 While in the foregoing however, there has thus been illustrated in the drawings and described in the specification such combination and arrangement of elements as constitute the preferred embodiment of this invention, it is desired to emphasize the fact that such minor changes in the matters of proportion and degree may be made in later adaptations of this device, as shall not alter the spirit of the invention as defined in the 30 35 appended claims.

What is claimed is:—

1. In a clothes line grip, a base portion formed with loops and a terminal spring arm, and jaws loosely mounted by said loops 40 and similarly engageable by said arm.
2. In an automatic clothes line grip, jaws loosely mounted on a base portion, and a resilient member formed integrally with said base portion for sliding contact with 45 said jaw in normally keeping the latter closed.

Copies of this patent may be obtained for five cents each, by addressing the "Commissioner of Patents,
Washington, D. C."

3. The combination with a spring grip including a base portion, jaws loosely connected thereto and a resilient arm integral with said base portion and slidable upon 50 said jaws, of a protector plate apertured to similarly slide upon said jaws.

4. The combination in an endless clothes line including a series of linked grips forming the upper portion of the clothes line 55 circuit when the latter is in use, means for transferring said grips to the lower portion of said circuit, and protector plates adapted to be of service automatically in said last named position.

5. In an automatic clothes line grip, a base portion formed with a terminal eye, an intermediate loop, and an integral resilient arm terminating in a larger loop, jaws, extensions formed on said jaws, eyes formed 65 on said extensions, corresponding pairs of eyes being loosely mounted upon said terminal eye and said intermediate loop of said base portion so that said jaws may be normally maintained in a closed position by the 70 action of said resilient arms in sliding upon a pair of the said extensions.

6. In an automatic clothes line grip, a base portion formed with a terminal eye, and an intermediate loop, a resilient arm 75 formed integrally upon said base portion, and angularly thereto, jaws, extensions formed on said jaws, eyes formed on said extensions to loosely mount said jaws in the said eye and loop of said base portion, an eye formed on said resilient arm for sliding engagement with one extension of each jaw, and links loosely positioning with respect to said base portion, grips of a series 80 in alignment.

In testimony whereof I affix my signature in presence of two witnesses.

HENRY AMACHER.
